UNITED STATES PATENT OFFICE

2,306,204

ELECTRIC ARC EXTINGUISHING
APPARATUSEugene W. Boehne, Drexel Hill, Pa., assignor to
General Electric Company, a corporation of
New York

Application October 2, 1940, Serial No. 359,363

5 Claims. (Cl. 200—144)

My invention relates to electric arc extinguishing apparatus having particular application to air circuit breakers of the magnetic blowout type employing an arc chute into which the arc is directed and extinguished.

The use of insulating arc chutes for interrupting high currents of moderate voltage circuits in air is well known and accepted practice. In general the arc is propelled by a magnetic blowout field into the arc chute and is stretched and elongated, thereby increasing the arc resistance, until the arc is extinguished. However, in the case of heavy currents, this method alone may be insufficient as the arc may be blown entirely through the chute without being extinguished.

In a more effective form of arc chute, it has been proposed appreciably to elongate the arc path within the chute by means of spaced interleaving ribs or fins extending from opposite walls of the chute so as to form a restricted tortuous passage generally of zigzag form for the arc as it proceeds through the chute. The closely confining walls of this passage also exact heat from the arc stream thereby further increasing the resistance of the arc.

A principal object of my invention is the provision of improved arc extinguishing apparatus of the aforesaid type comprising arc chute structure defining a tortuous arc passage in which both the configuration of the passageway and the magnetic forces of the arc current therein are so related as to provide more effective heat transfer between the arc stream and the passage side walls than heretofore attainable.

In previous arc chutes of this general type the interleaving fins were evenly spaced and made as plates of uniform thickness projecting perpendicularly from the side walls. Consequently the serpentine arc passageway defined by these interleaving fins comprises a series of transverse sections, parallel to and equidistant from adjacent sections, joined by short longitudinal end sections defined by the spacing between the fin extreme edges and the chute side walls. Such a configuration is shown, for example, in Patent No. 2,293,513, issued August 18, 1942, to L. J. Linde for "Electric air circuit breaker."

In serpentine arc paths of this type, active magnetic forces inherent in the arc current tending to urge the arc into closer relationship with the chute wall structure exist only at the loop tip ends and act outwardly toward the chute walls. That is, the magnetic forces of the arc current in the transverse sections, because of the latter lying parallel to and equidistant from one

another, tend to be neutralized so that the arc is maintained substantially centrally of the transverse passages without necessarily being in contact with either side wall. This obviously limits and retards the arc cooling action.

In accordance with my invention the inherent magnetic forces of the arc current are most effectively utilized to promote extensive heat transfer by providing in an improved arc chute a passageway for the arc in which adjacent transverse portions either do not lie parallel to each other or are in irregularly spaced relationship. Thereby a state of unbalanced magnetic interaction is established substantially along the whole length of the passageway. The resultant magnetic forces actively tend to displace the arc sideways from a central position in the passage into greater heat-transfer relationship with the passage side walls.

My invention will be more fully set forth in the following description referring to the accompanying drawings, and the features of novelty which characterize my invention will be pointed out with particularity in the claims annexed to and forming a part of this specification.

Referring to the drawings, Fig. 1 is an elevational view partly in section of the essential parts of an air circuit breaker embodying my invention, Fig. 2 is a sectional view taken along the line 2—2 of Fig. 1, Fig. 3 is a sectional enlarged view taken along the line 3—3 of Fig. 1, Fig. 4 is a partly diagrammatic view illustrating principles underlying the present invention, Fig. 5 is an enlarged sectional view generally similar to that of Fig. 2, Fig. 6 is a similar sectional view of another form of arc chute structure embodying my invention, Fig. 7 is a similar end sectional view of another modification of my invention, and Fig. 8 is a similar end sectional view of another form my invention may assume.

The air circuit breaker illustrated by Fig. 1 is of the magnetic blowout type and is shown for example in a form that is particularly adaptable for central stations and sub-stations wherein the circuit breaker unit can be bodily disconnected with respect to the stationary circuit. This form of circuit breaker is generally incorporated in metal-clad structure for vertical movement therein. However, since this feature forms no part of the present invention, a complete disclosure thereof is omitted in the interest of clearness.

Referring specifically to the circuit breaker including the contact structure and the arc extinguishing means, the relatively movable contact

structure comprises a fixed contact 1 and a movable contact 2 that is pivotally mounted at 3 on one of the circuit breaker studs and is operated by means of a reciprocally movable rod 4. The operating rod is suitably connected to an actuating mechanism (not shown) for operating the movable contact between closed and open circuit position. The contacts 1 and 2 are electrically connected to the lower ends of the breaker conductor studs 5 and 6 respectively which also serve as the terminals of the breaker unit. Accordingly, when the breaker is connected in series in a power circuit and the contacts 1 and 2 are separated, an arc may form across the gap indicated.

For the purpose of interrupting this power arc, an arc extinguishing structure generally indicated at 7 is mounted with respect to the contact structure so as directly to receive the power arc which is under the influence of the magnetic blowout fields produced by the coils 8 and 9. In the arrangement so far described, the arc extinguishing structure is similar to a conventional arc chute wherein the arc is formed at a narrow entrance part of the chute and is rapidly extended in the form of a loop through the chute.

Referring more particularly to Fig. 2, the arc extinguishing structure comprises closely spaced side walls 10 and 11 composed of arc resisting material, such as for example an asbestos compound or a suitable arc resisting ceramic material. Each side wall of the chute at its inner side facing the other wall is provided with a plurality of parallel rib-like fins or ridges 10' and 11' respectively. The ridges 10' and 11' are preferably integral with the side walls of the chute which are joined and suitably clamped together at the ends 12 and 13. The length and spacing of the ridges 10' and 11' are such that when the side walls 10 and 11 are clamped together, the ridges are interleaved with respect to each other, i. e., in staggered relation, so as to form a zigzag passage 14 having alternating salients into which the arc is driven at the entrance 15 of the arc chute 7.

As clearly shown by Fig. 1, which illustrates but half the extinguishing structure in detail, namely the side wall 11, the ridges extend parallel in spaced relation in a direction transverse to the direction of the movement of the arc as it passes from the entrance 15 into the chute. These ridges, as will be explained later in detail, are formed so that unbalanced magnetic interaction is established with respect to the adjacent sections of the arc to force a maximum amount of the total arc length against the side walls of the tortuous passage 14. In Fig. 2, the ridges are shown in cross section as broader at the base, gradually tapering toward the tips thereby defining a zigzag passage generally similar in form to that shown by Fig. 5.

It will be understood that my invention is not limited to the specific form of chute illustrated by Fig. 1 and that by way of example the longitudinally straight ridges, instead of being arranged in straight parallel relation as shown, may follow concentric curvilinear paths or paths radiating from the chute entrance.

As the arc formed between the separating contacts is driven by the magnetic blowout field into the entrance passage 15 of the arc extinguishing structure, there is comparatively little transverse deflection of the arc stream during this initial movement due to the fact that the ridges 10' and 11' are tapered along the longitudinal axis

from the exhaust end of the chute toward the arc entrance at 15. This arrangement is clearly illustrated by Fig. 3. As the arc is driven into the zigzag space defined by the interleaving ridges, the cross section of the arc is reduced as the arc more and more assumes a serpentine form. If a heavy current arc is to be interrupted, interruption may not occur until the arc has been moved well into the chute.

Up to the point of interruption, the blowout field continues to move the arc outward through the arc passage, thereby progressively lengthening the path of the arc as the amplitude of the zigzag path becomes greater. The arc is thereby 15 greatly lengthened and attenuated concurrent with very effective cooling due both to the large cooling surfaces of the ridges as the arc approaches the exhaust part of the chute and to my improved method of establishing unbalanced magnetic forces of the arc current for obtaining a greater degree of intimate contact between the arc stream and the effective cooling surfaces of the chute.

The switch contacts and the magnetic blowout structures can assume any preferred form and comprise no part of the present invention so that a brief description will be sufficient. The magnetic blowout coils 8 are electrically connected to the conductor stud 5 and to the arc runner 8' so that the arc current traverses the blowout coils in a manner well known in the art. Normally, the current is carried in the closed circuit position of the breaker by the spring biased contact 1', the current being shunted to the arcing contact at 1 upon opening of the breaker. As the arc is drawn by the movable contact 2, it is transferred to the arc runner 8' when it passes the position indicated by Fig. 1 so that the blowout coil 8, which is electrically connected as indicated to the conductor stud 6 is now connected in series with the arc current. Accordingly, the blowout coils are energized by the arc current to influence the arc in a well known manner, i. e., to project the arc into the chute in an ever expanding loop. For the purpose of utilizing the blowout field to the greatest extent, iron pole pieces are secured along the outer sides of the arc chute.

For the purpose of suppressing and confining within the arc chute exceptionally heavy overload or short circuit currents that may be sometimes encountered, an additional arc suppressing unit 16 is provided at the exhaust end of the arc chute. This unit comprises a compact grid-like structure which also freely vents arc gases generated within the chute. This arc suppressor unit forms no part of the present invention and is specifically disclosed and is claimed in the Linde patent supra. A detailed description of this unit is unnecessary for a complete understanding of the present invention, it being sufficient to state that the exhaust end of the zigzag arc passage opens into the grid-like suppressor unit for venting the chute gases.

The underlying principles of operation of my improved arc interrupting means for establishing unbalanced magnetic interaction, together with various forms my invention may assume, will now be explained. It has been stated that the resistance of the arc stream is progressively increased concurrent with lengthening and attenuating thereof as the arc is forced into a more and more tortuous path in the chute passage 14. This increase in arc stream resistance causes decrease of the arc current and also improvement of

the power factor of the circuit, all of which serve to aid interruption.

It can be stated that during interruption, the arc energy increases up to a point where the arc resistance in ohms equals the external circuit impedance in ohms. At this stage, maximum energy liberation occurs. The phase angle has shifted to 45° and the current is 70.7% of its value at zero power factor. With the continued movement of the arc into cooler regions of the chute, the arc resistance is further increased and a state soon exists in which the chute walls are capable of absorbing the arc heat energy at a rate exceeding that of the arc heat liberation. This state having been reached the arc may then be described as being on the "downhill side" toward interruption. Since the present invention is primarily concerned with alternating current circuit breakers, this arc phenomena is particularly advantageous since interruption generally occurs at the next current zero.

In the above described interrupting process involving progressive increase of the arc stream resistance, the cooling or heat transfer action plays the most important part and it is therefore essential that for most effective interruption the arc be forced into intimate heat transfer relation with the cooling surfaces of the chute. I accomplish this by so designing the tortuous arc path that unequal magnetic forces interact between adjacent portions of the arc stream so that extensive sections of the arc are biased by magnetic forces so as to hug the confining walls of the arc passage. This intimate contact between the arc stream and the chute structure obviously brings about a much higher rate of heat transfer from the arc stream than the case where the arc plays freely within the arc passage.

A graphical illustration will make clear the arc interrupting method above described. An electric arc is a conductor and is subject to all the laws of magnetic forces acting on conductors. The fundamental relation of the interacting force between two conductors is as follows:

$$F = \frac{KI_1 I_2}{d}$$

where:

K=Numerical constant

I₁=Current in one conductor

I₂=Current in other conductor

d=Distance between them

F=Force acting on each conductor

As is well known, this force acts through all non-magnetic materials.

Reference is now made to Fig. 4 which diagrammatically illustrates a single current carrying conductor A—B—C folded upon itself to form three parallel conductors positioned between rigid insulating walls W₁ and W₂. Let it be assumed that the initial spacing between the parallel conductors A and B is d₁ and that between the conductors B and C is d₂ and that by way of example d₂ is appreciably greater than d₁. The current I is of course equal in all three parts of the circuit so that the force acting on the center conductor B by the magnetic forces of the current traversing conductor A, which is restrained by the adjacent rigid wall W₁ can be expressed as follows:

$$F_1 = \frac{KI^2}{d_1}$$

Also the force acting on the same conductor B by the magnetic forces of the current traversing the

conductor C, which is also restrained by the adjacent rigid wall W₂ can be similarly expressed as:

$$F_2 = \frac{KI^2}{d_2}$$

According to first principles, the movable center conductor B will be moved by the interacting magnetic forces to a position where the net or resultant force acting on it is zero. In this position, the above relationships can be expressed as follows:

$$\frac{KI^2}{d_1} - \frac{KI^2}{d_2} = 0$$

15 or

$$\frac{KI^2}{d_1} = \frac{KI^2}{d_2}$$

It therefore follows that this relation will be satisfied only when d₁=d₂, i. e., when the spacing between the conductors A—B—C is equal and uniform.

Now let it be assumed that a cool insulating rigid surface (not shown) is positioned between the conductors B and C to prevent the conductor B from moving to its position of magnetic equilibrium. If now, we further assume that the conductor B is a portion of the arc stream, it will be apparent that the insulating wall below the conductor B would now be in intimate good heat transfer relation with the arc stream, i. e., the magnetic forces between the conductors A and B would cause the arc portion B to lay flat against and hug the restraining insulating wall. Since this force reacts equally in opposite directions, it also follows that the conductor or arc portion A also would be forced flat against the insulating wall W₁.

A similar analysis will readily show that if the conductors B and C are both held rigid, conductor A will be forced to move upward in the absence of the wall W₁ until d₁=d₂. However, in the present illustration, the conductor or arc portion A would be simply forced flat against the insulating wall. The above explanation clearly shows that if the arc, when confined in a passage of tortuous configuration, is spaced non-symmetrically with respect to adjacent portions thereof instead of symmetrically, the arc will be forced by the reacting magnetic forces more intimately against the adjacent passage walls defining cooling surfaces thereby extracting heat from the arc stream at a higher rate and greatly facilitating arc interruption.

Fig. 5, which is merely an enlarged and somewhat exaggerated view of the arc passage structure shown by Fig. 2, illustrates how the above principles are applied in a practical form. The ridges 10' and 11' of the chute side walls 10 and 11 respectively are nested in slightly spaced interleaving relation to form the tortuous zigzag arc path 14. As indicated by Fig. 3, this is representative of the form of the arc passage throughout the greater part of the chute toward the exhaust end. The cross-sectional area of the ridges 10' and 11' is shown as of pyramidal shape, i. e., of non-uniform thickness. Also the ridges are of such height that they form deep salients in the opposite wall structure. As shown, the ridge height is comparable to or greater than the corresponding ridge base width.

The effect of unbalanced magnetic interaction on the portions of the arc stream at the left of the center line indicated will at once be apparent from the foregoing discussion of Fig. 4. That is,

those portions of the arc at the opposite sides of the ridges 11' indicated by the spacing d_1 will be flattened against the opposite walls of the ridges 10' by reason of the resultant magnetic forces due to the inequality between the spacing d_1 and d_2 . The same is obviously true of the arc at the opposite side of the center line, i. e., the corresponding arc portions at that side will be flattened against the walls of the chute ridges 11'. The only points of magnetic equilibrium are along the center line itself, so it follows that the greater part of the arc stream is subjected to the more intensive cooling action above described.

Other important advantageous factors are involved in this particular zigzag configuration to establish the latter as the preferred embodiment of my invention. Referring again to Fig. 5, it has been shown and will now be evident that the unbalanced magnetic forces serve to drive the arc away from the tips of the pyramidal cross-sectioned ridges into the bases of the adjacent ridges so that the arc heat is directed into the sections of greatest mass in the chute structure for instantaneous heat absorption and toward the chute side walls where the acquired heat is readily dissipated. In addition, this increasing cross-section is particularly effective for rapidly draining the heat from the body of the ridges and also from the comparatively narrow tips where burning otherwise would be more pronounced, so that the chute structure is rendered longer-lived.

By way of example, it will therefore be evident in comparing the prior type parallel-side ridge to my improved tapered ridge, the cross-sectional area and depth of the two ridges being equal, that the tapered form is superior magnetically, physically and mechanically.

The essential form of the arc passage above described is defined by alternating salients, one salient having a transverse dimension (i. e., parallel to the center line) throughout an appreciable part thereof (i. e., between the tip and center line) that is appreciably less than the aligned transverse dimension of the adjacent alternating salient (i. e., the dimension d_1 as compared with d_2) so that an unbalanced state is thereby established between the magnetic forces of the arc current for causing the arc portions at opposite sides of said lesser transverse dimension (i. e., the dimension d_1) to be forced in opposite directions against the insulating walls of the chute passage in heat transfer relation thereto.

By way of example, I have found from comparative tests of two arc chutes identical in size, construction and material except that one was of the conventional symmetrical type and the other designed for unbalanced magnetic interaction in accordance with my invention that my improved chute was capable of interrupting a maximum current 1.8 times that of the conventional symmetrical chute even though the circuit voltage in the case of my chute was 1.17 times greater.

In the form of my invention shown by Fig. 6, which illustrates the exhaust end of the chute as in the case of Fig. 2, the opposing chute walls 20 and 21 are provided with spaced interlocking and interleaving ridges 20' and 21' respectively. These ridges form between each other and the cooperating chute walls an arc passage 22 of somewhat exaggerated serpentine shape and extend substantially parallel through the chute as in the case of Figs. 1 and 3.

For the purpose of providing magnetic unbalance for affecting the arc in the manner above

described, each ridge at its outer end is provided with an enlarged portion having a bulbous cross-sectional area as illustrated so as to establish a spacing d_2 for the corresponding loop of the arc. Each ridge near its base where it is united to the corresponding chute wall on the other hand tapers to a narrow neck so as to establish a comparatively small spacing d_1 for the reacting portions of the adjacent arc logs. It will therefore be seen, referring specifically to the arc at the left of the center line indicated, that the strong and predominant magnetic forces reacting through the space d_1 cause the arc portions at the opposite sides of the narrow neck to flatten against and hug the passage walls defined by the bulbous parts of the ridges 21'. The arc stream is thereby cooled at a high rate by the forced contact with the passage walls.

This effective cooling of the arc also takes place in a similar manner at the right side of the center line for the same reasons and since the only main points of magnetic equilibrium are along the center line as in the case of Fig. 5, it will be observed that the greater part of the arc stream is positively and effectively cooled by the heat transfer relation established with the chute passage walls.

The modification illustrated by Fig. 7, which shows the exhaust end of the chute as in the case of Figs. 2 and 6 is so closely related to the diagrammatic arrangement shown by Fig. 4 that the operation is believed to be clear without detailed description. The chute walls 30 and 31 are provided with interleaving fins or ribs 30' and 31' respectively, the fins 30' being narrow and appreciably spaced and the fins 31' being comparatively thick and closely spaced to form the unsymmetrical arc passage 32. Since this passage closely simulates the form of the conductor of Fig. 4, further description is believed to be unnecessary other than to state that the arc portions at the opposite sides of each narrow fin 30' are forced in opposite directions by the resultant magnetic forces into good heat transfer relation with the adjacent walls of the comparatively thick ribs 31'.

In the modification shown by Fig. 8, dissymmetry is accomplished by appreciable variations in the length and positioning of the cooperating fins. In this instance, the chute side walls 40 and 41 are each provided with fins, some of which are interleaving and others spaced in alignment. The fins 40' of the chute wall 40 are in part unequally spaced and receive certain fins 41' of the chute wall 41 in interleaving relation. However, other fins of the wall 41 indicated at 41'' are shown as of limited or "stub" length and in spaced alignment with the cooperating fins 40'. It will be apparent that in this design the arc is both lengthened by the interleaving arrangement and also attenuated at the gaps between the fins 40' and 41'' as well as being intensively cooled at the comparatively narrow loops where the fins 40' and 41' interleave. Further description of arc cooling action is believed to be unnecessary in view of the similarity between the arc paths of Fig. 7 and Fig. 8.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. Electric arc extinguishing apparatus comprising an insulating arc chute into which the interrupting arc is directed having side walls disposed in closely spaced relation so as to form a narrow elongated arc space, said walls on the sides facing each other having projecting therefrom elongated ridges extending generally in the direction of arc movement, ridges of one wall being spaced and interleaved with respect to ridges of the other wall so that together they form a restricted tortuous arc extinguishing passage of zigzag form extending through said chute and having a cross section characterized by alternating salients, interleaving ridges of said walls having a height at least equal to or greater than the width of the corresponding ridge base so that said ridges form deep salients in the opposite wall structure, the transverse dimension of one salient throughout a part of its height being materially less than the aligned transverse dimension of the adjacent alternating salient so that a material degree of magnetic unbalance is thereby established between the magnetic forces of the arc current along the opposite sides of said salients, said magnetic unbalance causing the arc portions at opposite sides of said lesser transverse dimension to be forcibly urged in opposite directions against the insulating wall of the chute passage in heat transfer relation thereto for materially cooling the arc stream.

2. Electric arc extinguishing apparatus comprising an insulating arc chute into which the interrupting arc is directed having side walls disposed in closely spaced relation so as to form a narrow elongated arc space, said walls on the sides facing each other having projecting therefrom ridges extending generally throughout said chute in the direction of arc movement, ridges of one wall being spaced in interleaving position with respect to ridges of the other wall to form a restricted tortuous arc extinguishing passage characterized by alternating salients, interleaving ridges of said walls having a height greater than the width of the corresponding ridge base so that said ridges form deep salients in the opposite wall structure, the cross sectional thickness of each ridge decreasing from the base thereof where it joins the corresponding chute wall to the tip so that a transverse dimension of one salient lying intermediate its tip and the transverse center line is materially less than the aligned transverse dimension of the adjacent salient whereby an unbalanced condition is established between the magnetic forces of the arc current in adjacent salients, said magnetic unbalance causing the arc portions at opposite sides of said lesser transverse dimension to be forcibly urged in opposite directions against the insulating walls of the chute passage for materially cooling the arc stream.

3. Electric arc extinguishing apparatus comprising an insulating arc chute into which the interrupting arc is directed having side walls disposed in closely spaced relation so as to form a narrow arc space, said walls on the sides facing each other having projecting therefrom ridges extending generally throughout said chute in the direction of arc movement, the ridges of one wall being spaced in interlocking position with respect to the ridges of the other wall so as to form a restricted tortuous arc extinguishing passage of serpentine cross section defined by alternating salients, said ridges being comparatively narrow near the base joining the corresponding chute wall and increasing in width toward the ends thereof to form interlocking portions with the ridges on the opposite chute wall thereby defining alternating salients of bulbous form whereby dissymmetry is established between the magnetic forces of the arc current, said dissymmetry causing the arc portions at opposite sides of the narrow section of each ridge to be forced in opposite directions against the adjacent interlocking ridges in heat transfer relation thereto.
4. Electric arc extinguishing apparatus comprising an insulating arc chute into which the interrupting arc is directed having side walls disposed in closely spaced relation so as to form a narrow arc space, said walls on the sides facing each other having projecting therefrom ridges extending generally throughout said chute in the direction of arc movement, ridges of one wall being spaced in interleaving position with respect to ridges of the other wall to form a restricted tortuous arc extinguishing passage defined by salients extending in opposite directions, the cross sectional thickness of individual interleaving ridges being non-uniform whereby an unbalanced condition is established between the magnetic forces of the arc current at opposite sides of a salient, said unbalanced condition causing the arc portions at opposite sides of individual interleaving ridges to be forced by reacting magnetic forces against the side walls of adjacent ridges in heat transfer relation thereto.
5. Electric arc extinguishing apparatus comprising an insulating arc chute into which the interrupting arc is directed having side walls disposed in closely spaced relation so as to form a narrow arc space, said walls on the sides facing each other having projecting therefrom ridges extending generally in the direction of arc movement, ridges of one wall being shaped with respect to ridges of the opposite wall so that ridges of both walls are both interleaved and interlocked with respect to each other, said interlocked ridges being arranged in sufficiently spaced relation to form a restricted tortuous arc extinguishing passage of serpentine form as viewed in cross section transverse with respect to said arc movement.

EUGENE W. BOEHNE.
